SACK AND BAG SEAL AND FASTENER

John Thomas Greenslade, Victoria, British Columbia, Canada

Application March 26, 1945, Serial No. 584,951

1 Claim. (Cl. 150—3)

1

My present invention relates to improvements in closures and sealing means for bags, sacks and the like.

It is of importance in closing bags or sacks used for sugar, flour, grain and the like to completely seal up the opening through which the bag has been filled so that the contents will not be spilled therefrom, and it has been customary in the past to sew up such bags. It is obvious that if such sewing is to be effective, it is a slow, painstaking process.

The object in the present invention is therefore to provide a bag, sack or the like having sealing means which effectively prevent the spilling of sugar, flour, grain, feed and the like without the necessity of sewing up the opening of the bag. A further object is to provide a bag, sack or the like having closure means which, while effectively sealing the bag, are quickly and easily engaged and disengaged.

According to the invention there is therefore provided a bag or the like having a mouth adapted to be collapsed to bring opposite side walls thereof together, these side walls being of substantially equal length, and a flap member rectangular in shape is secured along one edge to the inside of one of the side walls of the mouth along a line substantially parallel to the outer limit of the mouth. This line along which the flap is secured is removed from the outer limit of the mouth so that there is formed between the flap and the outer portion of the side wall to which it is connected what may be called a pocket which will receive the outer portion of the other side wall when it is folded over. This so-called pocket is in fact open at the sides. Means are preferably then provided on the flap member adapted to pass through the side wall to which it is not connected and thereafter to be passed through the side wall to which it is connected and thereafter to be engaged by retaining means on the side wall to which it is connected. In a preferred form, these means pass also through the side to which the flap is attached before engagement by the retaining means.

According to a modification of the invention, the flap member extending from side to side of the bag mouth is replaced by a plurality of relatively narrow tabs secured at one end to one side wall and having secured to the other end means for engaging retaining means on said side wall after having passed through the opposite side wall.

The invention will now be described by reference to the accompanying drawings, in which

2

Figure 1 is a perspective view of the mouth of a bag embodying the preferred form of the invention;

Figure 2 is a vertical section through the bag mouth shown in Figure 1;

Figure 3 is a detail in section of the mouth of the bag in sealed condition showing one form of closure means;

Figure 4 is similar to Figure 3 showing a modified form of closure means;

Figure 5 is a vertical section through the bag mouth according to a modified form of the invention;

Figure 6 is a fragmentary view of the inside 15 surface of the bag shown at the left hand side of Figure 5, and

Figure 7 is a vertical section through the mouth of another modified form of closure.

In the drawings wherein like characters of reference are used to designate like or similar parts throughout the several views:

Figures 1 and 2 show a portion of the bag wherein adjacent to the outer extremity of the mouth 10 is conveniently reinforced with cardboard 11 or similar material. As shown in Figure 2, the mouth of the bag may be folded over the cardboard or the like. The result is to form what may be called a rim portion of the mouth of the bag which is of increased body.

Substantially at the bottom of this rim on one of the side walls and which is marked 10a, there is attached an elongated rectangular flap 12. This flap 12 is secured to the side wall 10a only along its lower edge and extends outwardly 35 towards the outer limit of the mouth of the bag forming between the flap 12 and the outer portion of the wall 12a what may be termed for the sake of convenience an open ended pocket 13 adapted to receive the outer portion of the side wall 10b when it is folded over on top of the flap 12.

Holes 14 and 15 are formed in the side walls 10b and 10a respectively and the flap 12 is provided with closure members 16 adapted to pass 45 through the holes 14 and 15 (in that order) when the outer part of the side wall 10b is first folded over the flap 12 and then the outer part of the side wall 10a is folded over the outer part of the side wall 10b. In the modification shown in Figure 4, the member 16' has formed at its end a tubular portion 17' and on the outside of the outer portion of the side wall 10a there is attached a tab 18' adapted to engage this tubular portion 50 and hold the two side wall portions and the flap 16 in engagement as shown in Figure 4.

In Figures 1 to 4 the member 16 is shown as projecting from the side of the flap 12. Alternatively, the flap 12 may be made narrower so that it does not project so far towards the outer extremity of the mouth of the bag and the member 16' may be secured to the edge of the flap 12 as shown in Figure 4.

Referring to Figures 3 and 4, it will be seen that any contents of the bag are effectively prevented from escaping by the seal formed by the firm engagement of the side wall 10b between the flap 12 and the side wall 10a. Any contents which might escape would have to pass around the end of the flap 12, along the width of the flap 12 between it and the side wall 10b, around the end of the side wall 10b held in engagement with the side wall 10a, and along the contacting surfaces of the side walls 10a and 10b.

In Figures 5 and 6 there is shown a modification in which the flap 12 is replaced by a plurality of tabs 21 secured at one end to the side wall 10a and having at its other end a closure member with retaining means which may resemble the tubular part 17 shown in Figures 1 to 3. These tabs are passed through holes 22 formed in the side wall 10b, and the side wall 10b is folded over so that its edge 23 will be in contact with or very close to the inside surface of the side wall 10a between the point at which the tab is secured to the side wall 10a and the hole 24. The tabs 21 are then passed through the hole 24 from the inside of the bag, the side wall 10a is folded down on top of the outer surface of the side wall 10b and the side wall 10a is held in position folded against side walls 10b by retaining means which may be the tab 18 described with reference to Figures 1 to 3.

As will be understood, it is not necessary that the portion of the mouth which has been described as the rim should be reinforced as shown in Figure 2. Such reinforcing may be entirely dispensed with or may be provided in only one side wall, as is shown in Figure 5, the cardboard or other reinforcing material 25 being provided only in the side wall 10b.

In the modified form shown in Figure 7, the sack or bag 10 is reinforced at the mouth on both sides of the opening at 26 and 26a. A reasonable number of openings 28 and 29 are made in the side walls, for instance, four or more. The open-

ings in one side wall are located higher than those in the remaining side wall, and the flap member 27 runs the width of the sack and is attached to said first side wall. The hooks 30 first enter the hole 24. Parts 10a and 26 are then folded over flap 27, and parts 10b and 26a are then folded over parts 10a and 26, and the metal hooks enter the hole 29 to seal the sack.

From the foregoing, it is believed that the operation and advantages of my invention will be apparent, but it is pointed out that changes in form size, shape, materials, construction and arrangement of parts is permissible and within my broad inventive concept. Interpretation of the scope of my invention should only be conclusive when made in the light of the subjoined claim.

I claim:

A bag having upper end portions adapted in closing the bag to be folded one upon the other into a position substantially normal to the sides of the bag, said end portions being provided with a plurality of openings adapted to register when said end portions are in folded position, a flap within the mouth portion of the bag secured below the foldable end portions along one longitudinal edge only to a side of the bag, said flap being adapted to underlie said end portions when said end portions are folded, a corresponding plurality of elements each having an angularly formed rod like portion and a tubular end portion, supported by the flap for passage through said openings when said end portions are folded, and means carried by one of said end portions for engagement with said elements to retain the bag closed.
